CHILD'S VELOCIPED

Stuart Nelson Mann, Derby, N. Y.

Application May 12, 1955, Serial No. 35,954

Term of patent 7 years

(Cl. D34—15)

Fig. 1 is a side elevation of a child's velocipede showing my new design;

Fig. 2 is a plan view thereof; and

Fig. 3 is a front elevation.

I claim:

The ornamental design for a child's velocipede, as shown.
